United States Patent

Des. 235,187
Patented May 27, 1975

235,187

CANISTER LID OR SIMILAR ARTICLE

Walter B. Achenbach, Toledo, Ohio, assignor to Owens-Illinois, Inc., Toledo, Ohio

Filed Oct. 24, 1973, Ser. No. 409,150

Term of patent 14 years

Int. Cl. D7—01

U.S. Cl. D7—131

FIG. 1

FIG. 3

FIG. 1 is an elevational view of a canister lid or similar article showing my new design;

FIG. 2 is a top plan view thereof; and

FIG. 3 is a bottom view thereof.

I claim:

The ornamental design for a canister lid or similar article, as shown and described.
